Primary Examiner — Cathron Brooks*Assistant Examiner* — Richard Kearney(74) *Attorney, Agent, or Firm* — Mark C. Johnson; Johnson | Datal(57) **CLAIM**

The ornamental design for a weighted bracelet, as shown and described.

DESCRIPTION

FIG. 1 is a top perspective view of a weighted bracelet in accordance with the present invention;

FIG. 2 is a top plan view of FIG. 1;

FIG. 3 is a side elevation view of FIG. 1;

FIG. 4 is a front elevation view of FIG. 1; and,

FIG. 5 is an exploded view of FIG. 1 with the non-claimed implements of the weighted bracelet removed.

The broken lines shown in the drawings depict portions of the weighted bracelet which form no part of the claimed design.
